[57] **CLAIM**

The ornamental design for a hub for a tape reel, as shown and described.

DESCRIPTION

FIG. 1 is a front elevational view of a hub for a tape reel, showing my new design, the rear elevational view being a mirror image thereof;

FIG. 2 is a right-side elevational view thereof, the left-side elevational view being a mirror image thereof;
FIG. 3 is a cross sectional view thereof, taken along line 3—3 in FIG. 1;

FIG. 4 is a top plan view thereof; and
FIG. 5 is a bottom plan view thereof.

FIG. 2

FIG. 3

FIG. 4

FIG. 5
